UNITED STATES PATENT OFFICE

2,284,021

UPPER-HOLDING DEVICE

Charles A. Robinson, Salem, Mass., assignor to
 United Shoe Machinery Corporation, Flemington, N. J., a corporation of New Jersey

Application July 12, 1941, Serial No. 402,109

11 Claims.

(Cl. 12—107)

This invention relates to devices for use in the manufacture of shoes for holding end portions of uppers in lasted position. The invention is herein illustrated by reference to the lasting of the toe ends of welt shoes, but it will be understood that under appropriate conditions it is of more general applicability.

In the lasting of the toe ends of welt shoes the marginal portion of the upper is commonly wiped inwardly against a lip formed on the insole or against a shoulder otherwise provided on the insole, and it is the usual practice for the operator to fasten the toe end of the upper in lasted position by applying a binder wire around the toe against the upstanding margin of the upper and anchoring the wire to tacks driven into the shoe at the opposite sides of the forepart of the shoe bottom. Objects of the present invention are primarily to provide an upper-holding device which may be applied and fastened to the shoe more quickly and conveniently than such binder wire and which may be used repeatedly in lasting different shoes. To these and other ends, the upper-holding device herein shown comprises a flexible binder which may be conveniently made of wire and is of suitable length to extend around the lasted margin of the toe-end portion of the upper, and members connected respectively to the opposite ends of this binder and arranged to serve as levers fulcrumed on the shoe to force the binder lengthwise of the shoe and thus to apply it tightly to the margin of the upper. More particularly, in the illustrative embodiment of the invention, these levers, which are hung on the ends of the binder, are provided with comparatively short arms having pointed ends arranged to penetrate the upper in locations opposite the lip of the insole and with longer arms whereby the operator swings the levers in planes substantially parallel to the shoe bottom while fulcrumed on the shoe at their pointed ends, the longer arms being provided with hook portions arranged to engage the lip of the insole to hold levers in place and thereby to retain the binder in upper-holding position. It should be understood, however, that consistently with the objects in view the invention in some of its aspects is not limited to a device having levers arranged thus to swing in planes substantially parallel to the shoe bottom or arranged to be held in place on the shoe in the particular manner herein illustrated.

The novel features of the invention will now be more particularly described with reference to

the accompanying drawing and thereafter pointed out in the claims.

In the drawing,

Fig. 1 is a view showing a portion of a toe-lasting machine and illustrating how an upper-holding device constructed in accordance with the present invention may be applied to a shoe;

Fig. 2 is a perspective view of the toe portion of the shoe with the upper-holding device applied thereto; and

Fig. 3 shows the device inverted as it appears before it is applied to a shoe.

The upper-holding device herein shown includes a flexible wire binder 2 of suitable length to extend around the lasted margin of the toe-end portion of the upper of a welt shoe and provided with loops 4 at its opposite ends. Hung on these loops are levers 6 provided with holes 8 through which the binder 2 is threaded before the loops are formed. The holes are so arranged that each lever 6 has a comparatively short arm 10 and a longer arm 12. The short arms 10 are provided with points 14 adapted to penetrate the marginal portion of the upper in locations opposite the usual lip a of the insole to cause the levers to fulcrum on the shoe as they are swung in planes substantially parallel to the shoe bottom in applying the binder 2 to the shoe. The longer arms 12 are so formed as to provide hook portions 16 arranged to extend inwardly over the lip of the insole and curved to extend heightwise of the shoe and outwardly toward the inner face of the lip, the ends of these hook portions having points 18 adapted to penetrate the lip from its inner face to assist in holding the levers in place after the binder has been applied to the shoe.

The invention is herein illustrated by reference to its use in lasting shoes in a power-operated toe-lasting machine such as disclosed in United States Letters Patent No. 2,160,846, granted on June 6, 1939, on an application of F. C. Eastman's and A. F. Pym's. Such a machine is provided with toe-lasting wipers 20 which in time relation to other operations performed by the machine are advanced and closed to wipe the marginal portion of the toe end of the upper inwardly over the feather of the insole and against the lip of the insole, the lip being supported against such inward pressure of the wipers by a plate 22 in engagement with its inner face. As disclosed in the above-mentioned Letters Patent, the machine comes automatically to a stop after the wipers have thus wiped the upper inwardly and have been raised slightly to decrease their pres-

sure on the upper heightwise of the shoe, to permit the operator to apply binder wire preliminarily about the toe between the upper and the wiping faces of the wipers. When the machine is again started, the wipers are further lifted a short distance and are also partially retracted and opened to permit the operator to pull the wire farther inwardly against the upstanding margin of the upper, after which they are again moved downwardly and are advanced and closed to apply their full pressure to the upper and to press the binder against the upper. The machine then comes to a stop a second time to permit the operator to fasten the binder to the shoe and to sever it from the source of wire supply. In using an upper-holding device such as herein shown in lasting a shoe with this machine the operator, supporting the device by its levers 6, may apply it preliminarily about the toe with the binder 2 pulled part way in between the wipers and the upper by bodily movements of the levers when the machine first comes to a stop as above described, and will thereafter pull the binder fully in against the upstanding margin of the upper as more readily permitted by the wipers after the machine has again been started. Before the machine again comes to a stop the wipers will press the binder against the upper in the same manner as when acting on binder wire such as used heretofore. After the machine has come to a stop the second time, the operator will force the pointed ends 14 of the levers 6 into the upper in locations opposite the lip of the insole with the levers extending generally widthwise of the shoe and will then swing the levers in directions lengthwise and widthwise of the shoe in planes substantially parallel to the bottom of the shoe in the manner illustrated in Fig. 1. In these movements the levers will pull the binder still more tightly against the margin of the upper. The levers are thus swung by the operator to positions where their hook portions 16 extend over the lip of the insole as illustrated in Fig. 2 with their pointed ends 18 penetrating the lip at its inner side, so that the levers are held by the shoe effectively against displacement with the binder 2 in upper-holding position. By reference to Fig. 3, which shows the parts in substantially the same relation as in Fig. 2, it will be evident that when the device is in place on a shoe the levers 6 extend generally lengthwise of the shoe and that by reason of the relation of the holes 8 to the pointed ends 14 of the levers which penetrate the upper, the portions of the binder along the sides of the toe are held close to the upstanding margin of the upper.

It will be understood that upper-holding devices provided by this invention are adapted for use, in place of binder wire such as commonly used heretofore, in lasting shoes not only with machines such as shown in the previously mentioned Letters Patent but with various machines. In lasting shoes, for example, with well-known bed-lasting machines having manually operated wipers, such devices will be applied to the shoes at the same time when it has been customary heretofore to apply the binder wire, the binder 2 being pulled inwardly against the upstanding margin of the upper under the wipers by a pull applied by the operator to the levers 6 and being then forced more firmly against the upper by swinging movements of the levers fulcrumed on the shoe in the manner hereinabove described. It will be understood that such an upper-holding device will remain on the shoe until the upper

10 materials have become permanently set in lasted position, after which the device will be removed from the shoe prior to the welting operation.

Having described the invention, what I claim 15 as new and desire to secure by Letters Patent of the United States is:

1. A device for holding an upper in lasted position around an end of a shoe, said device including a binder for engaging the upper around the end of the shoe, and members connected to said binder and arranged to serve as levers fulcrumed on the shoe independently of each other to force the binder lengthwise of the shoe while thus engaging the upper.

15 2. A device for holding an upper in lasted position around an end of a shoe, said device including a binder for engaging the upper around the end of the shoe, and members connected respectively to opposite ends of said binder and 20 having pointed ends adapted to penetrate the shoe, said members being arranged to serve as levers fulcrumed on the shoe at their pointed ends to force the binder lengthwise of the shoe while thus engaging the upper.

20 3. A device for holding an upper in lasted position around an end of a shoe, said device including a binder for engaging the upper around the end of the shoe, and members connected respectively to opposite ends of said binder and arranged to serve as levers fulcrumed on the shoe to force the binder against the upper by swinging movements of the members, said members having means for engaging the shoe to hold them against reverse swinging movements and thereby 30 to retain the binder in upper-holding position.

30 4. A device for holding the marginal portion of an upper in lasted position against a lip or shoulder on an insole around an end of the insole, said device including a flexible binder for 40 engaging the marginal portion of the upper around the end of the insole, and members connected respectively to opposite ends of said binder and arranged to serve as levers fulcrumed on the shoe to force the binder lengthwise of the shoe by swinging movements of the members 45 lengthwise and laterally of the shoe.

45 5. A device for holding the marginal portion of an upper in lasted position against a lip or shoulder on an insole around an end of the insole, said device including a flexible binder for 50 engaging the marginal portion of the upper around the end of the insole, and members connected respectively to opposite ends of said binder and having pointed ends adapted to penetrate the upper, said members being arranged to 55 serve as levers fulcrumed on the upper at their pointed ends in locations opposite the lip or shoulder of the insole to force the binder lengthwise of the shoe.

55 6. A device for holding the marginal portion of an upper in lasted position against a lip or shoulder on an insole around an end of the insole, said device including a flexible binder for 60 engaging the marginal portion of the upper around the end of the insole, and members connected respectively to opposite ends of said binder and arranged to serve as levers fulcrumed on the shoe to draw the binder tightly about the marginal portion of the upper, said members 65 having portions arranged to engage the insole to hold them in place and thereby to retain the binder in upper-holding position.

65 7. A device for holding the marginal portion of an upper in lasted position against a lip or shoulder on an insole around an end of the in-

sole, said device including a flexible binder for engaging the marginal portion of the upper around the end of the insole, and members connected respectively to opposite ends of said binder and having pointed ends adapted to penetrate the upper, said members being arranged to serve as levers fulcrumed on the upper at their pointed ends in locations opposite the lip or shoulder of the insole to draw the binder tightly about the marginal portion of the upper by movements of the members in planes substantially parallel to the bottom of the shoe, portions of the members being movable inwardly over the insole and arranged to engage the insole to hold them in place and thereby to retain the binder in upper-holding position.

8. A device for holding the marginal portion of an upper in lasted position against a lip on an insole around an end of the insole, said device including a flexible binder for engaging the marginal portion of the upper around the end of the insole, and members connected respectively to opposite ends of said binder and arranged to serve as levers fulcrumed on the shoe to draw the binder tightly about the marginal portion of the upper by movements of the members in planes substantially parallel to the bottom of the shoe, said members having portions arranged to engage the inner side of the lip of the insole to hold them in place and thereby to retain the binder in upper-holding position.

9. A device for holding the marginal portion of an upper in lasted position against a lip on an insole around an end of the insole, said device including a flexible binder for engaging the mar-

5 ginal portion of the upper around the end of the insole, and levers hung respectively on opposite ends of said binder, said levers having comparatively short arms with points thereon adapted to penetrate the shoe to cause the levers to fulcrum on the shoe and having also longer arms whereby they may be swung to draw the binder tightly about the marginal portion of the upper.

10. A device for holding the marginal portion of an upper in lasted position against a lip on an insole around an end of the insole, said device including a flexible binder for engaging the marginal portion of the upper around the end of the insole, and levers hung respectively on opposite ends of said binder, said levers having comparatively short arms arranged to fulcrum on the shoe and longer arms whereby they may be swung to draw the binder tightly about the marginal portion of the upper, said longer arms being provided with hook portions arranged to extend over the lip of the insole to hold the levers in place by engagement with the lip and thereby to retain the binder in upper-holding position.

15 11. A device for holding the marginal portion of an upper in lasted position against a lip or shoulder on an insole around an end of the insole, said device including a wire binder arranged to extend around the marginal portion of the upper and having looped ends, and levers hung on said looped ends and arranged to fulcrum on the shoe while penetrating the shoe to draw the binder tightly about the marginal portion of the upper.

CHARLES A. ROBINSON.
